Application December 1, 1948, Serial No. 62,928

2 Claims. (Cl. 40—156)

1

This invention relates to picture frames and particularly to the means on the back of the frame enabling it to be hung on a wall or the like.

In frames such as those provided for photographs, the picture or photograph in the form of a paper sheet is usually replaceable by the user, and the frame therefore usually includes a removable backing plate normally forced between the front and rear flanges of the frame rim and thereby pressing the picture against the glass front. A folding easel is frequently provided on the back to support the frame in standing position on a horizontal surface such as a desk or the like. When, however, the user desires to hang the picture on a wall, it becomes necessary to secure a wire across the frame, or to provide on the back, a ring, loop or other support-engaging device adapted to be hooked on to a supporting member such as a tack, brad, screw, hook or the like, driven into and projecting from the wall. Such support-engaging devices are used only when the easel is not used and hence the cost of supplying and assembling the device is frequently wasted. Even if the device is used to hang a picture, it does not permit the frame to be hung in other than a single position subject to tilting and determined by the location of the support-engaging member.

The present invention therefore contemplates the elimination of separate or distinct support-engaging devices, and the utilization of the modified frame parts themselves to perform the functions of such devices.

The invention further contemplates the provision of one or more support-receiving slots located at selected points of the edges of and extending through the backing plate and designed to receive the free end of a fixed support, whereby the support directly engages or hooks behind the inner edge of the rear flange of the frame.

The invention further contemplates the provision in a frame of the usual type of a slotted backing plate to permit a supporting member to pass into a space provided therefor, into contact with the frame rim, whereby properly to suspend the frame and the picture therein.

The various objects of the invention will be clear from the description which follows and from the drawing, in which

Fig. 1 is a rear elevational view of a picture frame to which the invention has been applied and showing particularly the novel backing plate.

Fig. 2 is a perspective view of the slotted backing plate.

2

Fig. 3 is a partial vertical sectional view and partial side elevational view of the picture frame as it appears hung upon a hook projecting from a wall.

Fig. 4 is a fragmentary rear elevational view of the frame and its parts, showing the frame hanging on a brad.

Fig. 5 is a fragmentary vertical sectional view of the suspended frame, taken on the line 5—5 of Fig. 4.

The invention is herein illustrated as applied to a well known rectangular frame consisting of the rim 10, the glass sheet 11, the picture sheet 12 and the backing plate 13. The rim 10 is of generally U-shaped cross section having a front flange 14, a substantially parallel rear flange 15 on three sides of the frame and a connecting flange 16. The glass sheet 11 rests against the rear face of the front flange and is inserted into place by sliding it in front of the pair of oppositely disposed rear flanges, from that end at which the rear flange is omitted (Fig. 1). The picture is similarly inserted into place on the rear face of the glass and the backing plate 13 finally forced into place in the same manner, the thickness of the plate being such as to force the picture against the glass and to hold the various sheets frictionally in place, the plate being preferably of cardboard or similar some what compressible material for that purpose.

Preferably at the mid point of one long edge and of one short edge of the rectangular backing plate 13, suitable similar slots 17 and 17a respectively are made through the sheet. Each slot is of sufficient width to permit the passage therethrough of a suitable support such as a tack, nail, brad, picture hook or the like having a head at its free end or an upwardly extending part designed to enter the space 18 (Fig. 5) directly in front of the rear flange 15, which space would have been filled by the edge of the backing plate had not the slot 17 or 17a been made in said edge. The closed inner end of the slot is preferably rounded as at 19 to avoid weakening the backing plate. The length of the slot is preferably greater than the width of the flange 15 to expose the inner part of the slot for access to a supporting member from the rear of the frame.

As shown in Fig. 5, to hang the picture frame, the head 20 of the brad 21 extending from a wall or similar surface is inserted into the inner end of the selected slot 17 or 17a whereafter the frame is permitted to drop on to the brad and is released. The upper projecting part of the brad 20 thereby enters the space 18 and the

weight of the frame is transmitted through the edge 22 of the flange 15 to the brad upon which the frame is thereby suspended.

The slot being at the middle of the edge of the frame, the frame is properly balanced, hangs straight and does not tilt. The frame rim 10 is usually made of metal, wood or the like relatively rigid material amply able to withstand the weight of the entire frame thereon, thereby providing a rigid structure, there being no separate support-engaging element to pull out of the frame under stress. Obviously, the larger the head on the supporting member, the more of the head projects upwardly and enters the space 18 and the less chance there is of the frame slipping off the member. In Fig. 3, therefore, a hook 23 of suitable length is illustrated, having a portion to be fastened to the wall 24. By selecting the slot 17 or 17a, the picture may be hung either with the shorter edge or the longer edge uppermost as desired to correspond to the position of the picture in the frame rim.

By securing a suitable folding easel 25 to the backing sheet 13 and beveling the free end edge of the easel as shown in Fig. 1, the frame may be made to stand on a horizontal surface with either the long or the short edge thereof uppermost, in which case, the provision of the slots 17 and 17a saves the cost of the additional support-engaging element now customarily used on frames of the type here involved to adapt them to be hung.

It will be seen that we have provided a simple and inexpensive means permitting a picture frame to be hung in a selected position wherein it is automatically balanced, untilted, and with the required edge uppermost and that the invention is well adapted for the purposes intended. While a certain specific embodiment of the invention has herein been shown and described, it is obvious that various changes may be made therein within the spirit of the invention defined in the appended claims.

We claim:

1. In a picture frame assembly, a rectangular rigid metallic rim, each side but one of the rim comprising a front flange, a rear flange in rearward spaced relation to the front flange and a connecting flange of approximately the width of the rear flange joining the front and rear flanges, said one side of the rim having a front flange but omitting the rear flange to permit the insertion of picture-holding members into the rim and between the front and rear flanges of the other sides, a glass constituting one of the picture-holding members removably arranged between the front and rear flanges of the rim and of substantially the same length and width as that of

the rim, a compressible cardboard backing sheet of sufficient thickness to press a picture against the glass and to press the glass against the front flange and inserted between the glass and the rear flange, said sheet being self-held frictionally in contact with and in front of the rear flange on three sides of the rim removably to fill the space inwardly of the connecting flange and rearwardly of the glass, said backing sheet having an elongated slot therein of greater length than the width of the rear flange and extending inwardly from an edge of the sheet at a mid-point of and perpendicular to said edge whereby a portion of said slot is exposed inwardly of the inner edge of the rear flange and the remainder of the slot is concealed in front of the rear flange, the rear flange being imperforate at the slot.

2. In a picture frame assembly, a rigid rim having a front flange, a rear flange in rearward spaced relation to the front flange and a connecting flange joining the outer peripheries of the front and rear flanges, and a compressible backing sheet removably positioned against the front face of the rear flange and being of substantially the same overall length and width as that of the rim, said sheet being arranged with the marginal portions thereof within the rim and between the front and rear flanges, said sheet having an elongated slot therein of greater length than the width of the rear flange and extending inwardly from an edge of the sheet at a mid-point of said edge, that part of the slot at the marginal portion of the sheet being normally in front of and concealed and obstructed by the rear flange, and the remainder of the slot extending inwardly past the inner edge of the rear flange and being exposed and accessible from the rear of the rim, the rear flange being imperforate at the slot and the inner edge of the rear flange at said slot being adapted to rest by gravity on a support arranged in the slot thereby to suspend the picture frame assembly.
